(57) **CLAIM**

I claim the ornamental design for a cigarette lighter cap, as shown and described.

DESCRIPTION

FIG. 1 is a top plan view of the cigarette lighter cap, showing my new design;

FIG. 2 is a bottom plan view of my design;

FIG. 3 is a front elevation view thereof, the rear elevation being identical;

FIG. 4 is a side elevation view thereof, right side elevation and the left side elevation being identical;

FIG. 5 is a perspective view thereof; and,

FIG. 6 is a perspective view thereof when the cigarette lighter cap has been placed onto a cigarette lighter and attached to a lanyard reel, the broken line showing of a cigarette lighter and a lanyard reel is for illustrative purposes only and forms no part of the design.
